UNITED STATES PATENT OFFICE.

DANIEL BAKER DIMICK, OF BIRMINGHAM, ALABAMA.

PATTERN FOR CASTING PIPE.

Original application filed January 31, 1924, Serial No. 689,810. Divided and this application filed September 26, 1924. Serial No. 740,096.

To all whom it may concern:

Be it known that I, DANIEL BAKER DIMICK, a citizen of the United States, residing at Birmingham, in the county of Jefferson and State of Alabama, have invented certain new and useful Improvements in Patterns for Casting Pipe; and I do hereby declare the following to be a full, clear, and exact description of the invention, such as will enable others skilled in the art to which it appertains to make and use the same.

The present invention relates to improvements in patterns for casting pipe and this application is a division of my copending case Serial No. 689,810, filed January 31, 1924, entitled Apparatus for casting pipe.

The object of the invention is to provide an improved pattern having a flexible connection with the machine for screwing it out of the sand and provided with means to rough the sand in order that the molten metal will lie thereagainst.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation, on an enlarged scale, of the pattern and driving head.

Figure 2 is a longitudinal section taken through the parts shown in Figure 1.

Figure 3 is a bottom plan view of the driving head.

Figure 4 is a cross section taken on the line 4—4 in Figure 2, and

Figure 5 is an enlarged fragmentary section taken through that portion of the pattern which contains the roughing pins.

The pattern is provided with a thickened collar portion 20, adapted to fit rather loosely within the inner and outer annular flanges or rings 21 and 22 upon the lower part of the driving head 12. The rings 21 and 22 of the driving head are reinforced at proper points, and at these points are made registering perforations 23 for receiving the pins 24, the pins passing in through the perforations in both the rings 21 and 22 and alining perforations in the pattern collar 20. Preferably, only two pins at diametrically opposite points are inserted, and as aforesaid,

there is a certain looseness in the fit of the collar within the rings. This secures the very desirable result of permitting the pattern 11 to adjust itself to a correct position with respect to the mold and the sand therein, and the mold will be unaffected by any variations in movement of the driving head or the shaft 9. In this manner, a truer mold cavity is produced.

Now, referring more particularly to Figures 2, 4 and 5, numerous pins or small steel picks 25 are shown as fitted through appropriate openings made in the wall of the pattern 11 and projecting beyond the interior wall thereof, where the same are sharpened. These pins or picks are preferably arranged in off-set or staggered relation, and they are placed at only a small cylindrical section of the pattern 11, preferably a short distance up from the base of the pattern. The function of these pins is to rough the slick or polished sand.

In the operation of the device, the sand slinger is caused to throw in the sand to the mold about the pattern during the rotation of the pattern on the casting table, which table preferably rotates on ball bearings and is very true. The table turns at the rate of approximately eight revolutions per minute. The compactness of the ram can be regulated in three ways, namely, speed of the revolving table, speed of the sand slinger motor, and rate of feed of sand into the hopper of the sand slinging machine. It requires about two minutes to throw the sand into the mold to complete the operation. The entire operation is mechanical and a perfect ram on all parts of the corrugations or threads is obtained.

The pattern is then screwed upwardly and out of the sand, being driven by the pins 24 of the head 12, the connection being a flexible one as heretofore described. During this movement of the pattern, the pins 25 will "rough up" the polish and slick sand, without, however, materially disturbing this sand, and the lower section of the pattern will tend to press back this roughed sand, but it will not slick or polish it.

After the pattern is withdrawn, the molten metal is poured into the mold, and a relatively thin walled continuously cylindrical corrugated cast pipe is produced, all in a single operation without any joints.

It will be noted that the spiral corruga-

tions of the pattern 11 extend to both outside and inside surfaces so that what may be called a duplex action is had upon the sand in the mold. The pattern is machined in such a way that there is an even thickness of metal throughout; therefore, when the pattern is screwed upward and out of the mold, it forms, through this duplex action, simultaneously a spiral corrugated 5 mold in the outer member, and a spirally corrugated mold on the inner member. Thus there is produced by a single operation a mold cavity having spirally corrugated interior and exterior walls for producing in 10 one casting operation a spirally corrugated pipe having the corrugations upon both inside and outside surfaces. The pattern thus differs from those cases in which a screw produced a thread upon one surface of the 15 sand only.

It is obvious that various changes and modifications may be made in the details of construction and design of the above specifically described embodiment of this invention without departing from the spirit thereof, such changes and modifications being restricted only by the scope of the following claims.

What is claimed is:—

- 30 1. In an apparatus for casting pipe, a pattern having a continuously cylindrical spirally corrugated wall for screwing axially out of the sand cavity in a mold, said pattern having means for roughing the sand during its movement therethrough.
- 25 2. In an apparatus for casting pipe, a pattern having a continuously cylindrical spirally corrugated wall for screwing axially out of the sand cavity in a mold, and numerous relatively off-set pins projecting inwardly from the pattern at one cylindrical
- 35 40

cal section thereof spaced from the lower end of the pattern, said pins adapted to rough the sand, and the remaining lower, smooth corrugated portion of the pattern 45 adapted to press back the roughed sand.

3. A pattern for cast metal pipe having a continuously cylindrical spirally corrugated wall for screwing out of the sand cavity in a mold whereby to produce a seamless cast 50 metal pipe.

4. In an apparatus for casting pipe, a pattern having a continuously cylindrical spirally corrugated wall externally and internally for screwing axially out of the sand cavity in a mold, said pattern having means for roughing the sand during its movement therethrough.

5. In an apparatus for casting pipe, a pattern having a continuously cylindrical spirally corrugated wall externally and internally for screwing axially out of the sand cavity in a mold, the outer thread or spiral corrugation is in step or in pitch with the inner spiral or threaded corrugation, and numerous relatively off-set pins projecting inwardly from the pattern at one cylindrical section thereof spaced from the lower end of the pattern, said pins adapted to rough the sand, and the remaining lower, smooth corrugated portion of the pattern 60 adapted to press back the roughed sand.

6. A pattern for cast metal pipe having an outer and inner continuously cylindrical spirally corrugated wall in which the outer thread or spiral corrugation is in step or in pitch with the inner spiral or threaded corrugation for screwing out of the sand cavity in a mold whereby to produce in one operation a seamless cast metal pipe.

DANIEL BAKER DIMICK.
